UNITED STATES PATENT OFFICE

EDWIN F. GUTH, OF ST. LOUIS, MISSOURI

LIGHTING FIXTURE

Application filed November 23, 1927. Serial No. 235,187.

My invention relates to that class of fixtures of the well known Brascolite type, as covered by my Reissue Patent No. 14,680.

My invention has for its object, to construct 5 a fixture of that type which will have a higher efficiency than is at present obtainable; and this I accomplish by making the enclosing bowl very much smaller than is possible under existing conditions.

10 My invention has for its further object, so to shape the bowl, and to construct it of such material, that it will be free from glare, which is well known to be one of the most detrimental features of lighting units. As is also 15 well known, the intensity of the light is much greater as the shield nears the source, and as a consequence the glass must not be close to the lamp bulb.

As illustrated, I have overcome this by 20 constructing my bowl of parabolic shape, and of materially greater density where the bowl is closest to the lamp. This may be accomplished by materially thickening the glass of the bowl at its lower portion where it is near 25 the lamp bulb, but it may be found desirable in practice to employ some medium which will reduce the brightness to the desired amount. Such a construction, however, would be most inefficient, in so far as the 30 working plane is concerned; and I avoid this by providing a large opening in the bottom of the bowl, so that a direct light of great intensity is distributed on the working plane, immediately below the fixture, over an area of 35 a 25° radius.

A further advantage resulting from the use of a bowl with this large opening in the bottom is, that although it enables the fixture to deliver to the useful plane a direct 40 light which can be controlled within an area of 50°—25° each side of the nadir, yet the filament is shielded from the eye, so that no deleterious effects are produced by the light coming to the user, notwithstanding the high 45 intrinsic brilliancy of the filament of the high-powered lamp.

The provision of this opening also enables me to avoid a very seriously objectionable feature present in all units of this type, i. e., 50 drop of efficiency through service, for the

large opening in the base of the bowl permits the dust, insects, etc., to fall out; while forming it as I do fills in the inner surface so that hindrance to service efficiency, induced by the lodgment of dust on the inside of the bowl, 55 is largely obviated. The large opening also establishes ample circulation, thus insuring a cool lamp base, and also making it easy to clean the bowl when necessary.

Being able to use a small bowl, I am enabled 60 to decrease the cost without lessening the efficiency, for I can use a reflector of smaller diameter, and still control all the upwardly directed light rays, within the area of the reflecting plane. This reduction in size, without sacrifice of efficiency, enables the production 65 of a very inexpensive unit which is free from objectionable glare.

My invention has for its further object, to provide a socket which will adjustably support the fixture, and will also electrically insulate it therefrom. My construction will also provide for complete protection for the lead-in wires.

My means of accomplishing these objects 75 may be more readily understood by having reference to the accompanying drawings, which are hereunto annexed and made a part of this specification, in which—

Fig. 1 is a vertical sectional elevation; and 80 Fig. 2 is a fragmentary bottom plan view.

Similar reference numerals refer to similar parts throughout the entire description.

As shown in the drawings, I provide a socket 1, which is preferably made of suitable 85 insulating material. (As illustrated, this socket is the one described in my co-pending application, Serial No. 184,873.) From this socket 1 is suspended a reflector 2, of the canopy type, the lower surface, 3, of which is 90 preferably porcelain-enameled. The socket 1 has a thread 4 on its outer surface, which supports the fixture. A cap 5 is mounted at the top of the socket 1, and is screwed on to the central stud 6 of the standard junction or 95 outlet box 7. In the drawings I have shown a plurality of loops 8, formed out of the reflector 2 adjacent the socket 1, to which loops 8 are attached rods or wires 9 which support the bowl 10, which is preferably formed of 100

translucent glass; but it will be obvious that any desired form of fastening for these rods 9 may be employed. An electric lamp bulb 11 is mounted in the socket 1 and depends downwardly therefrom. As clearly seen in 5 the sectional view, the bowl 10 is formed with a very large opening 12 in its bottom, and the side wall is very thick at its lower portion 13, tapering to a point 14 as the surface gets farther from the light source and can be thinned 10 without producing glare. A suitable switch 15 is mounted on the upper part of the reflector canopy 2, and has depending from it the usual chain pull 16, for switching the current on and off as desired.

15 For the purpose of full disclosure of my invention I have described in some detail a specific embodiment thereof; but it will be apparent that numerous changes might be made in the physical embodiment of my invention 20 within the scope of the claims, and I do not desire, therefore, to be understood as limiting myself, in the broader aspect of my invention, to the specific construction shown and described.

25 Having described my invention, what I regard as new, and desire to secure by Letters Patent of the United States, is:

1. In a lighting fixture, a source of light, 30 a bowl formed of light diffusing material surrounding said light source, the thickness of the material in said bowl decreasing with the distance from the light source whereby substantially uniform brightness of the bowl is obtained.

35 2. In a lighting fixture, a source of light, a bowl formed of light diffusing material surrounding said light source, the thickness of the material in said bowl decreasing with the distance from the light source whereby substantially uniform brightness of the bowl is obtained, there being a large opening in the 40 bottom of the bowl.

EDWIN F. GUTH.
